COMBINED PULL CORD LOCK AND DRAPEY SUPPORT

Orville T. Stall, 7908 Chatfield Ave., Whittier, Calif.

Filed Mar. 19, 1962, Ser. No. 69,324

Term of patent 14 years

(Cl. D21—1)

FIG. 1 is an isometric view of a combined pull cord lock and drapery support, embodying my new design;

FIG. 2 is an end elevational view;

FIG. 3 is a side elevational view;

FIG. 4 is an end elevational view showing the end opposite that shown in FIG. 2;

FIG. 5 is a side elevational view showing the side opposite that shown in FIG. 3; and

FIG. 6 is a bottom plan view thereof.

The laterally extending toothed arm has been omitted in FIGS. 3 and 5 of the drawings for convenience of illustration.

I claim:

The ornamental design for a combined pull cord lock and drapery support, as shown and described.
